UNITED STATES PATENT OFFICE.

JOHN AUGUST CHRYSANDER, OF NEW YORK, N. Y.

CALENDAR.

1,375,567.

Specification of Letters Patent. Patented Apr. 19, 1921.

Application filed August 27, 1920. Serial No. 406,266.

To all whom it may concern:

Be it known that I, JOHN AUGUST CHRYSANDER, a citizen of the United States, and resident of the city of New York, borough 5 of Manhattan, county of New York, and State of New York, have invented a new and Improved Calendar, of which the following is a full, clear, and exact description.

It is well appreciated that numerous calendars are put upon the market in the form of a memorandum pad. These calendars usually include a leaf for each day, week or month, and have printed matter or other identifying marks affixed to their leaves, a 15 blank space being left, which blank space serves in the nature of a memorandum space for noting all appointments, expenses, etc.

Further, subsequent to the filling of one leaf corresponding to a day, week or month, 20 it has been customary to sever the same from the body of the calendar so that no permanent record of past events is provided by a device of this nature.

With this in view, I have constructed a 25 device in the nature of a calendar, which is not necessarily limited to this adaptation, and in which a plurality of memorandum spaces are provided, the leaves forming these memorandum spaces being capable of 30 being disposed in such a manner that it is unnecessary to sever them from the pad of the calendar so that a permanent record is provided.

A further object of my invention is the 35 construction of a device of this nature which shall not alone permit the keeping of a permanent record, but which shall be constructed in such a manner as to provide means permitting of the disposition of completed leaves, so that the neat appearance of 40 the device as a whole will be preserved, and the completed leaves will be kept in a position at which they are not liable to accumulate dust or other defacing marks.

Reference is had to the attached sheet of 45 drawings as illustrating one practical embodiment of my invention, and in which—

Figure 1 is a front view of a calendar constructed in accordance with my invention, and showing the leaves forming a part 50 of the same in their normal position.

Fig. 2 is a sectional side view taken along the line 2—2 of Fig. 1, and

Fig. 3 is a similar sectional view, but 55 showing certain of the leaves of the calendar or pad moved to the position at which they

form a part of the permanent record to be provided by means of my invention.

In these views the reference numeral 5 indicates any suitable type of backing sheet, 60 to which is affixed by any suitable securing means, such as staples 6, a pad of leaves 7, which leaves, as has been shown in Fig. 1 may conveniently bear printing upon their faces, identifying the individual days in the 65 month, and providing blank spaces for memoranda to the side thereof.

Contrary to the conventional construction which would require that each of the leaves upon being completed would be either severed from the pad 7 or pinned in a recessed portion so as to relieve the underlying sheet, I provide a slot 8 through the body of the backing sheet 5 and preferably parallel to the upper edge of the pad 7.

By this construction, upon a leaf being completely filled in the same may be folded back through the slot 8, as has been illustrated in Fig. 3, thus relieving the underlying sheet, and at the same time rendering 80 it unnecessary to sever the completed sheet or to pin the same to the backing sheet 5 so that a careless appearance is presented.

It will be understood that the leaves of the pad 7 if extending flush against the rear 85 face of the backing plate 5 would, upon sufficient leaves having accumulated, cause the backing plate 5 to not lie parallel to the surface of the wall to which it was affixed, and with this in view the backing sheet 5 is 90 formed with a further cut-out portion 9 extending through a portion of this sheet corresponding to approximately one half of the length of one of the sheets of the pad 7, it being noted however that the forward face 95 of the sheet 5 is formed with a recessed portion 10 extending throughout the balance of the length of one of these sheets.

By this construction it will be appreciated that one of the sheets of the pad 7 may be 100 passed through the opening 9 subsequent to its having been threaded through the slot 8, and by virtue of the fact that the lowermost portion of the leaves will be in a position intermediate the rearmost leaf of the pad 105 7 and the forward face of the recessed portion 10, the completed leaves will be retained in the position indicated in Fig. 3. At this position the completed leaves will be at all times held so that they will not act 110 as a detrimental factor to the appearance of the calendar at the same time being pro-

tected from injury and the action of dust, etc.

Obviously numerous modifications of structure might readily be resorted to without departing from the spirit of my invention, which I claim as—

A pad, comprising a backing having a transverse slot a short distance from its upper end, an opening below and adjacent to the slot, and a recess in its front face, said

recess extending from the lower edge of the opening to within a short distance of the bottom of backing, and a plurality of superposed leaves secured to the front face of the portion of the backing between the slot and opening, whereby the leaves can be passed through the slot to the rear of the backing and then through the opening to lie in recess in the front face of the backing. 15

JOHN AUGUST CHRY SANDER.
